CLAIM

The ornamental design for a suture loading apparatus, as shown and described.

DESCRIPTION

FIG. 1 is a top plan view of an embodiment of a suture loading apparatus showing our new design;

FIG. 2 is a first perspective view thereof;

FIG. 3 is a rear elevational view thereof;

FIG. 4 is a second perspective view thereof;

FIG. 5 is a bottom plan view thereof;

FIG. 6 is a front elevational view thereof;

FIG. 7 is a third perspective view thereof;

FIG. 8 is a fourth perspective thereof;

FIG. 9 is a right side elevational thereof;

FIG. 10 is a fifth perspective view thereof;

FIG. 11 is a sixth perspective view thereof; and,

FIG. 12 is a seventh perspective view thereof.

The broken lines shown in the drawings are included for the purpose of illustrating portions of the suture loading apparatus and form no part of the claimed design.
